UNITED STATES PATENT OFFICE.

REINOLD BERRENBERG, OF BOSTON, MASSACHUSETTS.

HIGH-VACUA PUMP.

Application filed December 26, 1924. Serial No. 758,002.

To all whom it may concern:

Be it known that I, REINOLD BERRENBERG, a citizen of the United States, residing at Boston, in the county of Suffolk and State of Massachusetts, have invented certain new and useful Improvements in High-Vacua Pumps, of which the following is a specification.

This invention relates to that class of rotary pump apparatus designed to produce an extremely high degree of rarefaction and more particularly to metallic pumps for producing high vacua.

High vacua are finding a rapidly extending application in numerous branches of industry and it is highly important that effective means be provided for securing vacua. High vacua is required for exhausting nitrogen lamp bulbs, vapor lamps, mercury arc rectifiers, X-ray tubes, thermos bottles etc., and to be effective the pump must combine with a high capacity, a high limiting vacuum. A comparatively new field in which high-vacua pumps are necessary is radio, in which field the present invention is particularly efficient for evacuating the tubes used in that art for detecting and amplifying.

The object of the present invention is to provide a high-vacua pump of extreme simplicity of construction which is relatively cheap to manufacture and yet will produce and maintain a practically perfect vacuum.

In carrying out the object of the invention the type of pump selected is that embodying an eccentric rotor within the pump cylinder, two such pumps being connected in series, or tandem arrangement, so that what the first may lose the other takes up, and a single vane or abutment continuously engaging both rotors. By this means a final pressure of 0.0001 mm. of mercury, measured on a McLeod gauge, is readily obtained with a tandem pump the cylinders of which are only two inches in diameter.

To the accomplishment of this object and such others as may hereinafter appear as will readily be understood by those skilled in the art, the invention comprises the features and combinations of parts hereinafter described and then particularly pointed out in the appended claims.

The preferred form of the invention is illustrated in the accompanying drawings in which Figure 1 is a view, in side elevation, with the front cover of the tank removed; Fig. 2 is an enlarged view, in vertical longi-

tudinal section, through the center of the pump cylinders; Fig. 3 is a diagrammatic view illustrating the manner in which the rotors are turned to final shape; and Fig. 4 is an end view of the sliding vane removed from the pump.

In the embodiment of the invention illustrated on the drawings an air tight tank 2 is provided, having a removable cover (not shown) and flanges 4 for lag screws or bolts. Within the tank on its bottom 6 are rectangular bosses 8 and 9 with finished upper surfaces to support the pump casing 10. The pump casing comprises two cylindrical rotor chambers 12 and 14 both in one casting which forms a tangent, or Siamese, partition wall 15 between them. A boss is cast on the under surface of each rotor chamber and these are finished to engage the floor bosses, the casting being bolted in position as shown by Fig. 2.

Within the chambers 12 and 14 are the rotors 16 and 18 respectively. Rotor 16 is mounted eccentrically on a shaft 20 which is journaled in the front plate 22 and a rear plate (not shown). Rotor 18 preferably of like eccentricity is similarly mounted at the same angle as rotor 16 on a shaft 24 which is journaled in the front and rear plates and is made long enough to extend through the rear wall 5 of the tank. The exterior portion of the shaft 24 carries a driving pulley belted to suitable power. Shafts 22 and 24 carry gears 26 and 28 respectively, outside the front plate 22, the teeth of which mesh with the teeth of a central gear 30 which rotates idly on a stub shaft 32 carried by the front plate. The shaft 24 rotates in a manner to drive the rotor 18 in a clockwise direction and the gearing causes the rotor 16 to be driven in the same direction.

The tangent partition wall is cut through from side to side forming a horizontal slot 33 adapted to receive a sliding vane or rotor abutment having ends 34 and 36 engaging the circumferential surfaces of the rotors 16 and 18 respectively. The slot is deeper than required to receive the vane which has a slide leg 37 (Fig. 4) at each end bearing on the lower wall of the slot and maintaining the vane in the upper portion thereof. The slot is so located vertically that its major portion lies below the plane of the axes of the rotor shafts 20 and 24 thus permitting the central plane of the vane to lie in the plane of said axes when constructed and mounted as de-

scribed. The passage between the vane legs forms a horizontal port below the vane, that connects the rotor chambers 12 and 14. The pump casing has a central boss 40 at its top 5 which is cored during manufacture to produce inlet and outlet ports. The course of the air passing through the pump is indicated by arrows *a*, *b* and *c*.

A nipple 46 spans the space from boss 40 10 to the tank cover and, after passing therethrough, is joined to a tube 42 leading to the article to be evacuated, all as shown in Fig. 2. The tank is also provided with an opening 44, closed by a screw cap, through 15 which the lubricant may be introduced and the air, discharged from the port *b*, permitted to escape.

The rotors 16 and 18 are of special form 20 and effectually prevent leakage of air back to the article being evacuated. In order to prevent such leakage it is essential that communication between the ports *a* and *c* be absolutely prevented and likewise between the ports *b* and *c*. This function of perfect 25 disconnection between any two adjacent air ports is attained by specially forming the circumferential surface of the rotor members 16 and 18.

Heretofore, the rotors, in pumps of the 30 type described, have been true cylinders thereby offering merely a line contact with the inner wall of the rotor chamber. With such a rotor contact in the pump of the present invention it is obvious that, at the 35 time the sliding vane bears on the point of greatest rotor eccentricity (see position of rotor 18, Fig. 2), the inlet and outlet ports communicating with the rotor chamber will be connected through the air chamber at 40 the other side of the eccentrically mounted rotor. This permits the previously evacuated air to leak back, at each revolution of the rotor, through the port *a* and passage 46 or from the chamber of the second pump 45 stage back into the chamber of the first pump stage.

In accordance with the present invention the disadvantage of leakage is eliminated by providing a surface contact, instead of a 50 line contact, between the rotor and its chamber wall. This surface is of sufficient angular length to extend across and seal both ports at each side of the sliding vane when either rotor is in the angular position illustrated by the rotor 18 in Fig. 2, and to 55 keep one port sealed until the sliding vane becomes effective. To gain this end a solid cylinder 50 (Fig. 3), of two inch diameter in the present instance since this is the diameter of the rotor chamber, is mounted in the lathe on centers *x* that are eccentric by one sixteenth of an inch and the reduction in diameter, by turning, is continued until the 60 cylinder is almost one and three-quarters 65 inches in diameter. The work is removed

from the lathe while a sector 52 of the rotor is still bounded by a curved surface 54 on an arc of exactly one inch radius, although the remainder of its cylindrical surface is on an arc of very slightly in excess of seven-eighths of an inch radius. The turning of the rotor is stopped when the one inch radius arc is reduced to about one half an inch in length, since this is sufficient to overlap the far sides of the adjacent air port in either 70 rotor chamber when the contact surface of the rotor is opposite.

With this construction the surface 54 on each rotor serves to completely destroy communication between ports *c* and *a* or ports *b* and *c* when the point of greatest rotor eccentricity is opposite the sliding vane and to effectually overcome the leakage that necessarily occurs at this time when the rotor offers merely a line contact. As a result 80 the evacuation continues evenly and increasingly and the final reading on the gauge shows a substantially perfect vacuum.

The purpose of having the transverse connecting port *c* as close as possible to the 85 sliding vane will now be clear since the length of the contact surface 54 should be as short as possible for the most efficient operation of the pump. The vane is formed in two parts and the meeting faces, at substantially its center, are drilled to receive 90 springs 56 which act to maintain an air tight contact at all times between the vane and rotors.

The pump, in operation, draws the air 100 from the article attached to the tube 42 which passes through port *a* and into the rotor chamber 12. Here it is forced through port *c* by rotor 16, the contacting end of the sliding vane compelling the air to travel 105 around the rotor. The air is sucked through port *c* by the rotor 18 and forced by it through the outlet port *b* in to the tank above the level of the oil bath. From here 110 it may be removed at will, through the opening 44.

Particular attention is directed to the horizontal port *c* which, by connecting the rotor chambers below the sliding vane, permits the 115 series operation of the two rotors on the same body of air. Those skilled in the art will recognize at once the immensely greater efficiency of a tandem construction in which one pump supplements the other, over a superficially like construction in which the ports are so arranged that the two pumps operate alternately on different bodies of air. The extreme simplicity of construction will be apparent from the foregoing description, 120 only three parts being required for each pump i. e. the casing forming the cylinder, the rotor, and the rotor vane.

The nature and scope of the present invention having been indicated and the preferred embodiment of the invention having been 125

- specifically described, what is claimed as new, is:—
1. A tandem vacuum pump comprising a casing having two cylinders, a rotor in each cylinder, a tangent partition wall between said cylinders having a slot therethrough, a common rotor vane slideable in the upper portion of said slot whereby the lower portion below the vane forms a connecting port between the two cylinders, said casing having an inlet port for one pump and an outlet port for the other above said vane, and means for driving both rotors in the same direction.
- 15 2. A tandem vacuum pump comprising a casing having two cylinders, a rotor in each cylinder, a tangent partition wall between said cylinders having a slot therethrough, the major portion of which lies below the plane of the axes of the rotors, a common rotor vane in said slot having spaced slide legs bearing on the lower wall of the slot and maintaining the vane in the upper portion thereof, whereby the lower portion of the slot forms a connecting port between the two cylinders, said casing having an inlet port for one pump and an outlet port for the other above said vane, and means for driving both rotors in the same direction.
- 20 3. A tandem vacuum pump comprising a casing having two cylinders with a tangent partition wall between them, a rotor vane common to both cylinders slidably seated in said wall, a connecting port between the cylinders below the vane, an inlet port for one cylinder above one end of the vane and an outlet port for the other cylinder above the other end of the vane, and an eccentrically mounted rotor in each cylinder having a surface contact with the cylinder wall equal in angular length to at least the angular distance between the lower wall of said connecting port and the upper wall of the other port communicating with the cylinder.

REINOLD BERRENBERG.
